United States Patent Office

Des. 195,460
Patented June 18, 1963

195,460

ACOUSTICAL TILE OR SIMILAR ARTICLE

Wallace Lanz, New York, N.Y., assignor to Minnesota and Ontario Paper Company, Minneapolis, Minn.

Filed June 12, 1962, Ser. No. 70,516

Term of patent 14 years

(Cl. D18—2)

FIG. 2

FIGURE 2 is an edge view of said acoustical tile or similar article.

In FIGURE 1 the undisclosed side of the tile is substantially plain.

I claim:

The ornamental design for the acoustical tile or similar article, substantially as shown and described.
